(57) **CLAIM**

The ornamental design for a chair as shown and described.

DESCRIPTION

FIG. 1 is a front, top, and left perspective view of a chair showing my new design; FIG. 2 is a rear, bottom, and right perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; and, FIG. 9 is a front, top, and left perspective view of the chair where the chair is in an alternate configuration of use. The broken lines in the drawings depict portions of the chair that form no part of the claimed design.

1 Claim, 9 Drawing Sheets
